UNITED STATES PATENT OFFICE.

GEORGE EVERETT STEVENSON AND GEORGE R. STEVENSON, OF INDIANAPOLIS,
INDIANA.

GEAR-GRINDING MACHINE.

Application filed May 17, 1920. Serial No. 381,802.

To all whom it may concern:

Be it known that we, GEORGE E. STEVENSON and GEORGE R. STEVENSON, citizens of the United States, residing at Indianapolis, 5 in the county of Marion and State of Indiana, have invented a new and useful Gear-Grinding Machine, of which the following is a specification.

The object of our invention is to produce 10 a compact and efficient machine for simultaneously acting upon a plurality of circumferentially-spaced portions of an article, as, for instance, a plurality of teeth of a gear, or gear blank.

15 While the apparatus is of such character that, with readily perceptible modifications it may be utilized either for primary forming operations, or for finishing operations, we have illustrated, in the drawings, an embodiment especially designed for final finishing of gear teeth by grinding.

The accompanying drawings illustrate 20 our invention. Fig. 1 is a side elevation, in partial vertical section, of an embodiment 25 of our invention using grinding wheels having a grinding surface corresponding to the valley between two teeth; Fig. 2 a plan of the machine shown in Fig. 1; Fig. 3 a side elevation at right angles to the plane of Fig. 30 Fig. 1; Fig. 4 a section on line 4—4 of Fig. 1; Fig. 5 a fragmentary section of the ram and adjacent parts; Fig. 6 a view similar to Fig. 1 showing a modification utilizing cylindrical grinding wheels; Fig. 7 a plan 35 of Fig. 6; Fig. 8 an elevation in a plane at right angles to the plane of Fig. 6; and Fig. 9 a diagram showing the manner of developing the guide cams used in the form of machine shown in Figs. 6 to 9.

40 In the drawings, 10 indicates a suitable base provided with a vertical semi-cylindrical bearing 11, complemented by the semi-cylindrical cap 12. Journaled in the lower end of bearing 11—12 is a tubular 45 driver 13, held against axial movement by collar 14 and carrying a worm-wheel 15. At its upper end, driver 13 is semi-annular (as indicated at 13') and mates with a similar semi-annular portion 16' at the lower 50 end of a ram 16 mounted for rotation and axial reciprocation in the upper end of bearing 11 and projecting above the upper end thereof.

Ram 16 is provided with a central tubular

spindle 17 provided, at its upper end, with 55 a tapered socket 18 adapted to receive an arbor 19 upon which the gear, gear blank, or other article is to be held for manipulation. Extending through spindle 17, and into socket 18, is an ejector rod 20, adapted 60 to engage, and eject, the arbor 19, and the lower end of this rod rests upon a foot lever 21 by which it may be operated to eject arbor 19.

65 Mounted upon base 10 is a cylindrical basin 25 having a central tubular stud 26 coaxial with bearing 11. Journaled upon stud 26 is a crown gear 27, supported on ball bearings 28 and carrying a spur gear 29.

70 Formed in the edge of basin 25 are several (six in the present instance) half-bearings 30 which extend radially of the axis of bearing 11 and are complemented by similar half-bearings carried by a basin 31 75 which, in its major portion, is nested in gear 27 and is provided with an overhanging edge resting upon the upper edge of basin 25. Basin 31 carries a series of radially arranged bearings 32 which align 80 with bearings 30, and in each pair of bearings 30—32, we journal a shaft 33, one being outwardly extended to receive a driving pulley 34. Each shaft 33 carries a pinion 35 meshing with gear 27, and also carries, 85 at its inner end, a flexible extension 36, connected, at its inner end, with a shaft 37 journaled in a carriage 38 slidably mounted in a block 39. Each block 39 is held in place by bolts 40 which lie in arc grooves 90 41 formed in the bottom of basin 31, the arrangement being such that each block 39 may be angularly adjusted around the axis 95 of arbor 18 and each carriage 38 may be reciprocated along lines which will be parallel with radii from the axis of said arbor.

100 Meshing with gear 29 is a gear 45 carried by a vertical shaft 46 provided with a worm 47 meshing with a worm wheel 48 which is journaled on a shaft 48' carrying a pinion 49 meshing with a gear 50, which, in turn, meshes with a gear 51 carried by a crank-shaft 52 having a wrist-pin 53. Journaled on pin 53 is a pitman 54 which is also journaled on a pin 55 vertically adjustable in a slot 56 in ram 16 and projecting through a slot 57 in bearing 11.

105 Formed in basin 31 is an annular pocket

60 covered by an L-shaped ring 61. In pocket 60 is journaled a ring-gear 62 which is engaged by a gear 63 carried by a tubular shaft 64 journaled in a bearing 65 carried by basin 31 and carrying a bevel gear 66 which meshes with a gear 67 carried by a shaft 68 having a gear 69 which meshes with a gear 70 carried by a shaft 71 carrying a gear 72 meshing with a gear 73 on shaft 48'. A clutch 74, controlled by a shifting lever 75, controls connection between gear 48 and shaft 48'.

Thus far the mechanism in the two forms shown in the drawings are the same.

16 In the form of machines shown in Figs. 1-5, inclusive, each shaft 37 is provided with a grinding element 80, the periphery of which, in the present instance, is formed with a cross-section which exactly corresponds to the shape of the space desired between two adjacent teeth of a gear which is to be supported upon the arbor 19.

In order to gradually move the grinding elements inwardly to their final position, 25 each carriage 38 is provided with an outwardly extending pin 81, longitudinally adjustable on the carriage by means of a nut 82 and each of these pins is projected into the channel 60 and engaged by a cam ring 30 83 attached to gear 62 (Fig. 1), said cam ring having a series of cam notches 83', one for each pin 81.

As previously stated, the gear 62 is moved by means of the train 63-66-67-35 68-69-70.

Gear 70 is a splined on shaft 71 which is supported in bearings so as to be axially shiftable as well as rotatable.

Journaled on shaft 71 is the gear 72 having a clutch member 87 capable of mating with a clutch member 88, on shaft 71, the arrangement being such that with the parts in the positions shown in Fig. 1, shaft 71 will be clutched to and rotate with gear 72, 45 but when withdrawn slightly to the left, the shaft 71 will be free from gear 72 and may then be rotated by hand so as to rotate gear 70 and the driving train from that point to gear 62.

50 Meshing with gear 72 is a gear 73 carried by shaft 48' so that when clutch 88 is in engagement with clutch 87, gear 62 and cam 83 will be driven through the medium of gear 48.

55 Shaft 46 carries a bevel gear 90 at its lower end and this gear meshes with a bevel pinion 91 carried by a friction disk 92 journaled upon shaft 93. Shaft 93 carries a worm 94 which meshes with the worm gear 15. Splined upon shaft 93 and mating with the friction disk 92 is a friction disk 95 which is held in engagement with disk 92 by means of a weighted lever 96. Secured to shaft 93 is a gear 97 which meshes with 60 a larger gear 98.

Gear 98 carries a small gear 99 which meshes with a larger gear 100, and secured to gear 100, is a stop cam 101. Cam 101 is provided with a shoulder 102 under which the stop arm 103 is normally held by the weighted lever 104, the arrangement being such that rotation of shaft 93 is normally prevented by the stop arm 103, although there is a constant tendency toward such rotation, due to the action of disk 92 on disk 95. Engaging arm 103 is a one-way pawl 105 carried by a lever 106. One arm of lever 106 is connected by a toggle link 107 with a vertically movable plunger 108 connected to one arm of a bell crank lever 109, the other arm being connected to a plunger 110 projected through the shaft which carries gears 66 and 63 and into position to be engaged by one of carriages 38 whenever said carriage is permitted to move outwardly to its extreme by having cam 83 moved to a position to bring the deepest part of one of the cam notches 83' opposite its finger 81.

Each carriage 38 is normally urged outwardly by a spring 38', the arrangement being such that whenever cam ring 83' has been rotated enough to bring the deep part of one of the notches 83 opposite the fingers 81 of carriages 38, one of said carriages will thereupon be moved out into engagement with plunger 110 and said plunger acting through lever 109, plunger 108, link 107 and a lever 106, will move stop arm 103 out of engagement with the cam shoulder 102, the pawl 105 during that movement swinging freely from arm 103 so that said arm may be immediately moved back into engagement with the cam 101.

As soon as cam 101 is released by the outward movement of arm 103, the train of gears connected with cam 101 is set in motion, due to the action of disks 92-95, and a complete rotation of cam 101 is insured, said cam coming to a stop at the end of said rotation against arm 103. Rotation of the train of gears connected to cam 101 permits rotation of shaft 93 so as to rotate member 13 and thus rotate the ram an amount equal to the distance between the two teeth of the gear which is being acted upon, the train of gears connected to cam 101 being so proportioned as to permit this desired movement.

In the form shown in Figs. 6-9, inclusive, the grinding element is provided with a cylindrical periphery so that during a major portion of its operation, it acts at one edge only upon a comparatively small portion of the tooth and consequently means must be provided to rotate the gear carrying arbor during the radial movement of the grinding element. In order to accomplish this result, we provide a cam ring 120 instead of the cam ring 83 and this cam 125 130

ring is provided with a series of cam notches of peculiar form, to be hereafter explained.

It is apparent that in this form of cam ring 120 must at all times bear a definite angular relationship to the gear-carrying arbor. Consequently, shaft 68 is provided with an extension 121 which carries a gear 122 at its lower end. This gear meshes with a gear 123 carried by a gear 124 meshing 10 with a gear 125 which meshes with a gear 126 carried by a shaft 127 which shaft carries a worm 128 meshing with worm wheel 15.

In this form of the machine, we provide a gear 130 similar to gear 45, and carried by shaft 131 carrying a worm 132, meshing with a gear 133 carrying two gears 134 and 135. Gear 135 meshes with gear 136 which meshes with a gear 137 carried by the crank 20 shaft 52. Gear 134 meshes with gear 140 which meshes with gear 141 which takes the place of gear 72 in the other form and is connected to gear 70, the arrangement and proportions of the gears being such that, 25 where six grinding elements are provided, the cam ring 120 will be moved through $\frac{1}{6}$ of a rotation, while the gear-carrying arbor is rotated through an angular distance equal to the distance between the center lines of 30 two adjacent teeth of the gear carried by the arbor.

We claim as our invention:

1. The combination, with a suitable frame and a work-supporting spindle journaled 35 therein, of a support through which the spindle is projected, a tool-driving gear journaled on said support, a stationary carrier surmounting said gear, a support for a tool carriage mounted on said carrier and 40 angularly adjustable thereon, a tool carriage slidably mounted on said last-mentioned support, a rotatable tool journaled on said carriage, driving connections between said tool and the tool-driving gear, a cam rotatably mounted on the stationary carrier, 45 means carried by the tool carriage and engaging the cam, and means for rotating said cam.

2. The combination, with a suitable frame and a work-supporting spindle journaled 50 therein, of a support through which the spindle is projected, a tool-driving gear journaled on said support, a stationary carrier surmounting said gear, a support for a tool carriage mounted on said carrier, a tool carriage 55 slidably mounted on said last-mentioned support, a rotatable tool journaled on said carriage, driving connections between said tool and the tool-driving gear, a cam rotatably mounted on the stationary carrier, 60 means carried by the tool-carriage and engaging the cam, and means for rotating said cam.

3. The combination, with a suitable frame 65 and a work-supporting spindle journaled

therein, of a support through which the spindle is projected, a tool-driving gear journaled on said support, a stationary carrier surmounting said gear, a support for a tool carriage mounted on said carrier and angularly adjustable thereon, a tool carriage slidably mounted on said last-mentioned support, a rotatable tool journaled on said carriage, driving connections between said tool and the tool-driving gear, and means for 70 shifting the tool carriage on its support. 75

4. The combination, with a suitable frame and a work-supporting spindle journaled therein, of a support through which the spindle is projected, a tool-driving gear 80 journaled on said support, a stationary carrier surmounting said gear, a support for a tool carriage mounted on said carrier, a tool carriage slidably mounted on said last-mentioned support, a rotatable tool journaled on 85 said carriage, driving connections between said tool and the tool-driving gear, and means for shifting the tool carriage on its support.

5. The combination, with a suitable frame 90 and a work-supporting spindle journaled therein, of a support through which the spindle is projected, a tool-driving gear journaled on said support, a stationary carrier surmounting said gear, a support for a tool 95 carriage mounted on said carrier and angularly adjustable thereon, a tool carriage slidably mounted on said last-mentioned support, a rotatable tool journaled on said carriage, driving connections between said 100 tool and the tool-driving gear, a cam rotatably mounted on the stationary carrier, means carried by the tool carriage and engaging the cam, means for rotating said cam, means for axially reciprocating the 105 work-spindle, and means for rotating the work-spindle in synchronism with the cam movement.

6. The combination, with a suitable frame and a work-supporting spindle journaled 110 therein, of a support through which the spindle is projected, a tool-driving gear journaled on said support, a stationary carrier surmounting said gear, a support for a tool carriage mounted on said carrier, a tool carriage 115 slidably mounted on said last-mentioned support, a rotatable tool journaled on said carriage, driving connections between said tool and the tool-driving gear, a cam rotatably mounted on the stationary carrier, 120 means carried by the tool-carriage and engaging the cam, means for rotating said cam, means for axially reciprocating the work-spindle, and means for rotating the work-spindle in synchronism with the cam 125 movement.

7. The combination, with a suitable frame and a work-supporting spindle journaled 130 therein, of a support through which the spindle is projected, a tool-driving gear jour-

naled on said support, a stationary carrier surmounting said gear, a support for a tool carriage mounted on said carrier and angularly adjustable thereon, a tool carriage slidably mounted on said last-mentioned support, a rotatable tool journaled on said carriage, driving connections between said tool and the tool-driving gear, a cam rotatably mounted on the stationary carrier, means carried by the tool carriage and engaging the cam, means for rotating said cam, and means for axially reciprocating the work-spindle.

8. The combination, with a suitable frame and a work-supporting spindle journaled therein, of a support through which the spindle is projected, a tool-driving gear journaled on said support, a stationary carrier surmounting said gear, a support for a tool carriage mounted on said carrier, a tool carriage slidably mounted on said last-mentioned support, a rotatable tool journaled on said carriage, driving connections between said tool and the tool-driving gear, a cam rotatably mounted on the stationary carrier, means carried by the tool-carriage and engaging the cam, means for rotating said cam, and means for axially reciprocating the work-spindle.

30 9. The combination, with a suitable frame and a work-supporting spindle journaled therein, of a support through which the spindle is projected, a tool-driving gear journaled on said support, a stationary carrier surmounting said gear, a support for a tool carriage mounted on said carrier and angularly adjustable thereon, a tool carriage slidably mounted on said last-mentioned support, a rotatable tool journaled on said carriage, driving connections between said tool and the tool-driving gear, a cam rotatably mounted on the stationary carrier, means carried by the tool carriage and engaging the cam, means for rotating said cam, means for axially reciprocating the work-spindle, and means for rotating the work-spindle.

10. The combination, with a suitable frame and a work-supporting spindle journaled therein, of a support through which the spindle is projected, a tool-driving gear journaled on said support, a stationary carrier surmounting said gear, a support for a tool carriage mounted on said carrier, a tool carriage slidably mounted on said last-mentioned support, a rotatable tool journaled on said carriage, driving connections between said tool and the tool-driving gear, a cam rotatably mounted on the stationary carrier, means carried by the tool-carriage and engaging the cam, means for rotating said cam, means for axially reciprocating the work-spindle, and means for rotating the work-spindle.

11. The combination of a suitable frame, a work-supporting spindle carrier journaled

therein, means for axially reciprocating said spindle carrier, a driving member journaled in the frame co-axially with the spindle carrier and having a rotatably-interlocking, axially-shiftable connection with the spindle-carrier, and means for rotating said driving member.

12. The combination of a suitable frame, a work-supporting spindle carrier journaled therein, means for axially reciprocating said spindle carrier, a driving member journaled in the support coaxially with the spindle carrier and having a rotatably-interlocking, axially-shiftable connection with the spindle-carrier, means for rotating said driving member, said means comprising a pair of frictional driving elements, a stop mechanism normally preventing rotation of said driving member, and means for intermittently withdrawing said stop member.

13. The combination, with a suitable frame and a work-supporting spindle journaled therein, of a support through which the spindle is projected, a tool-driving gear journaled on said support, a tool arranged to act upon work carried by the spindle and driven by said gear, means for axially reciprocating the work spindle, a gear carried by the tool-driving gear, and driving connections between said last-mentioned gear and the means for reciprocating the spindle.

14. The combination, with a suitable frame and a work-supporting spindle journaled therein, of a support through which the spindle is projected, a tool-driving gear journaled on said support, a tool arranged to act upon work carried by the spindle and driven by said gear, means for axially reciprocating the work spindle, means for angularly advancing the spindle step by step, a gear carried by the tool-driving gear, and driving connections between said last-mentioned gear and the means for reciprocating and advancing the spindle.

15. The combination with a suitable frame, and a work-supporting spindle journaled therein, of a support through which the spindle is projected, a plurality of circumferentially-spaced tool carriages mounted on said support and movable toward and from the spindle, tool-supports carried by said carriages, a main driving gear journaled on said support, driving connections between said last-mentioned gear and the several tool-supports, and means for axially reciprocating the spindle.

16. The combination with a suitable frame and a work-supporting spindle journaled therein, of a support through which the spindle is projected, a plurality of circumferentially-spaced tool carriages mounted on said support and movable toward and from the spindle, tool-supports carried by said carriages, a main driving gear journaled on

said support, and driving connections between said last-mentioned gear and the several tool supports.

17. The combination with a suitable frame and a work-supporting spindle journaled therein, of a tool carriage movable toward and from the spindle, means for axially reciprocating said spindle, means for rotating the spindle, said means comprising a friction driving train, a stop member normally preventing rotation of the spindle, and means controlled by the movement of the tool carriage for intermittently withdrawing said stop member.

18. The combination with a suitable frame and a work-supporting spindle journaled therein, of a tool carriage movable toward and from the spindle, means for rotating the spindle, said means comprising a friction driving train, a stop member normally preventing rotation of the spindle, and means controlled by the movement of the tool carriage for intermittently withdrawing said stop member.

19. The combination with a suitable frame and a work-supporting spindle journaled therein, of a tool carriage movable toward and from the spindle, means for axially reciprocating said spindle, means for rotating the spindle, said means comprising a friction

driving train, a stop member normally preventing rotation of the spindle, and means for intermittently withdrawing said stop member.

20. The combination with a suitable frame and a work-supporting spindle journaled therein, of a tool carriage movable toward and from the spindle, means for rotating the spindle, said means comprising a friction driving train, a stop member normally preventing rotation of the spindle, and means for intermittently withdrawing said stop member.

21. The combination with a suitable frame and a work-supporting spindle journaled therein, of a plurality of circumferentially-spaced tool carriers, each having a tool-support and grouped around said spindle and movable toward and from the same, a driving gear, connections between said gear and the several tool-supports, a cam formed to act upon the several tool carriers and shift the same relative to the spindle, and driving connections between said gear and cam.

In witness whereof, we have hereunto set our hands at Indianapolis, Indiana, this third day of April, A. D. one thousand nine hundred and twenty.

GEORGE EVERETT STEVENSON.

GEORGE R. STEVENSON.
